10 Claims. (Cl. 73—39)

1

This invention relates to fluid pressure brakes and more particularly to apparatus for testing the operability of such brakes on a train of coupled railway cars prior to coupling the train to a locomotive.

Before a train of coupled railway cars are connected to or moved by a locomotive in a railway yard or terminal the brake system on the train must be charged with fluid pressure followed by a partial service reduction in pressure in the brake pipe to cause the brake controlling valve devices on the cars of the train to operate to apply the brakes and then move to their lap position for isolating the reservoirs on the cars from the brake pipe. With the brake pipe thus disconnected from the reservoirs on the cars leakage of fluid under pressure from the brake pipe must be determined by observation of a pressure gage connected to the brake pipe. If the leakage is excessive the cause must be determined and corrected. Otherwise, or after the cause of excessive leakage is corrected, a full service reduction in pressure in the brake pipe must be effected to effect a full service application of the brakes throughout the train following which an inspection must be made of every car to see that the brakes thereon have applied properly, that the travel of the brake cylinder piston on each car is correct and that the brake rigging is not binding or fouling. If the brakes are applied on each car properly then the brake pipe and brake equipment on the cars must be recharged to release the brakes on the cars following which each car in the train must again be inspected to see that the brakes thereon have released as intended.

In order to test a train as above mentioned either two men must be employed, one to operate a train testing device connected to one end of the train and an inspector to walk back along the train to make the required inspection as to the brakes being applied and then upon arriving at the end of the train opposite that to which the train testing device is connected he must signal back to the man at the train testing device to recharge the train for releasing the brakes, whereupon the inspector will walk back along the train to observe the brake release on the cars, or only one man may be employed, in which case he must operate the brake testing device to apply the brakes through the train then walk back along the train to check on the brake application on all cars after which he must return to operate the testing device to recharge the train following which he will again have to walk to the opposite end of the train to check on the release of the

brakes throughout the train and then return to the testing device. Obviously, if one man can check the brakes on a train of cars as above described, it is undesirable that two men be so employed, but if only one man is so employed it is undesirable that he have to walk the length of the train four times to make the required test.

The principal object of the invention is therefore the provision of an improved testing device whereby one man can make the above test on a train of cars by walking only once from the testing device to the opposite end of the train and then return.

To accomplish this object the one man will operate the improved testing device to apply the brakes through the train and then walk the length of the train to check on the application. Upon arriving at the end of the train opposite the testing device he will momentarily open the usual angle cock at the end of the last car to initiate a wave of pressure reduction in the brake pipe, the improved testing device being so constructed as to respond to such pressure wave to recharge the brake pipe and release the brakes on the train, following which he will return along the train to check on the brake release on the cars, thereby accomplishing the same result as heretofore required either two men or twice the amount of walking in the case of a single man.

Other objects and advantages will become apparent from the following more detailed description of the invention.

In the accompanying drawings; Fig. 1 is a diagrammatic view, partly in section and partly in outline, of my improved train testing device shown in testing relation to a train of railway cars; Figs. 2 and 3 are cross-sectional views of an operator's control device shown in Fig. 1 but with a valve in different positions than in Fig. 1; and Fig. 4 is a sectional view of a fluid wave responsive device shown in elevation in Fig. 1 and constituting a part of the testing device.

Description

45 In the drawing, the dot-dash line, designated by the reference numeral 1, encloses the brake testing device embodying the invention, reference numeral 2 designates a reservoir or other source of fluid at suitable pressure connected by a pipe 3 to a hose coupling 4 at one end of said device. The reservoir 2 may constitute a portion of an air supply system in a railway yard or terminal or may be the main reservoir of a locomotive. Reference numeral 5 designates a train of coupled cars through which there extends the usual

brake pipe 6 adapted at one end of the train to be coupled to a hose coupling 7 of the brake testing device 1. 6a designates the usual angle cock in the brake pipe 6 at each end of each car, all of which angle cocks in the train are adapted to be open except the one at the end opposite the end to which the testing device will be connected which latter cock will be closed during the testing of the brakes on the train except under a condition to be later described. While only six cars are shown in the drawing as comprising the train it is desired to point out that the train may be of any length.

The brake testing device, constituting the apparatus enclosed within the dot-dash line 1, comprises an operator's control device 3, a combined brake pipe charging, maintaining and reducing valve device 9, an equalizing reservoir 10, a fluid pressure wave responsive device 11, a fluid motor 12, cut-off valves 13 and 14, and a pressure gage 15.

The operator's valve device 3 may, for the purpose of illustration, comprise a casing to which there are connected a pipe 16 from the hose coupling 4, a pipe 17 leading to the valve device 9, and a pipe 18 also leading to said valve device and to the equalizing reservoir 10, and which casing contains a rotary plug valve 19 movable to three different positions by an operating handle 20. The three different positions of the plug valve 19 and handle 20 are shown in Figs. 1, 2 and 3 of the drawings, and may be called, respectively, lap position, brake pipe charging position, and brake application position.

The plug valve 19 is provided with a passageway 21 adapted in the lap position thereof (Fig. 1) to establish a communication between the pipes 16 and 17 and adapted in the brake pipe charging position (Fig. 2) to connect pipes 16, 17 and 18, while in the brake application position (Fig. 3) said passageway is adapted to connect pipes 16 and 17. The plug valve 19 also has a cavity 22 for use only in the brake application position of said valve in which position it is adapted to connect pipe 18 to a restricted exhaust port 23 opening through the casing around said valve to atmosphere.

The combined brake pipe charging, maintaining and reducing valve device 9 comprises a casing containing a movable equalizing abutment, preferably in the form of a piston 24, at one side of which is a chamber 25 open to pipe 12 and thereby to the operator's valve device 3 and equalizing reservoir 10, while at the opposite side of said piston there is a chamber 26 which is open through a pipe 27 to one end of the two cut-off valves 13 and 14. The piston 24 has a stem 28 extending into chamber 26 and connected to said stem is one arm of the bell crank 29 which is fulcrumed on a pin 30 in the casing. A brake pipe exhaust valve 31 arranged to control communication between chamber 26 and an exhaust passage 32 leading to atmosphere is provided on one end of a stem 33 extending through an opening in the other arm of bell crank 29. On the other end of stem 33 is a collar 34 arranged to be engaged by the bell crank 29 upon operation thereof by the piston 24 when moving in the direction of chamber 25 to open the exhaust valve 31. A spring 35 acting on the collar 34 is provided for at all other times maintaining the exhaust valve 31 closed. Beneath the arm of the bell crank 29 connected to the piston stem 28 there is disposed a brake

pipe pressure maintaining valve 36 which is contained in a chamber 37 open to the pipe 17. The valve 36 has a stem 38 extending through suitable openings in the casing into operative alignment with the arm of bell crank 29 connected to piston stem 28 and which, with the piston 24 in the position in which it is shown in the drawing and with the exhaust valve 31 seated, is adapted to be engaged by said arm. Upon movement of piston 24 in the direction of chamber 25 for opening the exhaust valve 31 the bell crank 29 is adapted to move away from the maintaining valve stem 38 but upon movement of said piston in the direction of chamber 26 after closing of the exhaust valve 31 said bell crank is adapted to engage stem 38 and open the maintaining valve 36 for establishing communication between chambers 37 and 26. A spring 39 acts on the maintaining valve 36 for at other times closing it.

The fluid pressure wave responsive device 11 may be of any suitable structure adapted to respond to a wave of reduction in pressure of fluid in brake pipe 6, initiated in a manner to be later described, for supplying fluid under pressure to actuate the motor 12, but, for the purpose of illustration, may be of the type disclosed in United States Patent No. 2,028,605 issued to E. E. Hewitt on January 21, 1936 and may therefore comprise a casing containing two, coaxially aligned, flexible diaphragms 41 and 42 which are spaced apart and clamped around their edges in the casing. Between the two diaphragms 41 and 42 there is provided in the casing a chamber 43. At the opposite side of diaphragm 41 there is a chamber 44 which is in constant communication with a pipe 45 leading to the end of cut-off valve 13 opposite that to which pipe 27 is connected. At the opposite side of diaphragm 42 there is a fluid pressure operating chamber 46. Extending into chamber 43 formed between the two diaphragms is a casing rib 47 in which there is provided a passageway 48 extending to the outside of the casing where it is connected to a pipe 49 leading to the fluid motor 12. The rib 47 extends to the center of diaphragms 41 and 42 and there is open through a restricted port 50 to the interior of annular valve seat 51 formed coaxially with and facing diaphragm 41.

The central portion of diaphragm 41 is clamped between two followers 52 and 53 while the central portion of diaphragm 42 is clamped between followers 54 and 55, the followers 53 and 54 being disposed in chamber 43 and connected together by spacers 56 engaging same and cap screws 57 extending through the followers 52 and 55 and having screw-threaded engagement with said spacers whereby said followers are rigidly secured to opposite sides of the respective diaphragms and the diaphragms are secured together for movement in unison. The follower 52 has a boss 58 extending into chamber 44 to provide within said boss a chamber 59 open through a central aperture in the diaphragm 41 and an aligned opening in the follower 53 to chamber 43 and also open through a port 60 to chamber 46. A check valve 61 loosely mounted in chamber 59 is provided for engagement with the valve seat 51, a spring 62 in the boss 58 acting on said valve for urging it into such engagement. The follower 53 is provided with one or more fingers 63 extending into its axial opening for engaging the check valve 61 for moving it out of contact with the seat 51 upon deflection of diaphragm 41 in an upward direction. Depend-

ing from the diaphragm follower 55 is a stem 64 the lower end of which is slidably mounted in a suitable bore in the casing. In the upper end of stem 64 there is a chamber 65 open through a port 66 to chamber 46 and containing a valve 67 arranged to cooperate with a seat for controlling communication between said chambers and the chamber 43 by way of a passageway through which extends a tapered stem 68 of said valve which stem upon deflection of the diaphragm 42 in an upward direction is adapted to engage the casing rib 47 for opening said valve. The chamber 46 is also constantly open to chamber 43 through chamber 65 and a port 69 in the follower 55. A bias spring 70 contained in chamber 44 acts to bias the diaphragms and associated parts in the direction of chamber 46.

The fluid motor 12 comprises a casing containing a piston 70 at one side of which is a pressure chamber 71 open to pipe 49. At the opposite side of piston 70 is a non-pressure chamber 72 through which there extends a piston rod 73 projecting from said piston and disposed for movement in the plane of movement in handle 20 of the operator's valve device 8. A spring 74 in chamber 72 acts on piston 70 for urging it to the position in which it is shown in the drawing when chamber 71 is void of fluid under pressure. Upon supply of fluid under pressure to chamber 71 such pressure acting on piston 70 is adapted to move said piston and rod 73 against the spring 74. A restricted port 75 opens pressure chamber 71 to atmosphere for releasing fluid under pressure from said chamber. The motor 12 is so arranged with respect to the operator's valve device 8 that when the piston 70 is in the position in which it is shown in the drawing the end of rod 73 will be withdrawn to a position out of the path of movement of the operator's control lever 20 to permit free movement of said lever to any one of its three different positions, but upon supply of fluid under pressure to chamber 41 to actuate piston 70 the rod 73 will be operated against the handle 20 for moving it from whatever position it may be in to its brake pipe charging position, in which it is shown in Fig. 2 of the drawing.

The cut-off valves 13 and 14 may be of any desired structure for opening and closing communication between the connected pipes in, respectively, an open position and a closed position of a handle 76. It will be assumed that with the handles 76 at right angles to the pipe connections between the valves and the respective pipes that the communications through the valves will be closed while with the handles pointed in the direction of such connections such communications will be open. It will be seen that the cut-off valve 13 is arranged to control communication between pipe 27 and pipe 45, while the cut-off valve 14 is arranged to control communication between pipe 27 and the hose coupling 7.

The pressure gauge 15 is of the duplex type having one pressure element (not shown) connected by a pipe 77 to a pipe 78 connecting the cut-off valve 14 to the hose coupling 7, and having other pressure element (not shown) connected by a pipe 79 to the equalizing reservoir 9 whereby said gauge will register the pressures in both the brake pipe 6 and said reservoir.

Operation

In operation, let it be assumed that the train of cars 5 has been coupled upon which it is desired to test the brakes, that all angle cocks 6a in the train are open except the one at one end

of the train and that the reservoir 2 is supplied with fluid under pressure for such testing purposes. The operator's test device 1 will then be connected at coupling 7 to brake pipe 6 at the opposite end of the train 5 and at coupling 4 to the reservoir pipe 3. The cut-off valve 14 in the testing device will be opened and the cut-off valve 13 closed.

Now to test the brakes on the train the operator's control device 8 will be moved to the brake pipe charging position (in Fig. 2) in which fluid under pressure from reservoir 2 will be supplied from pipe 16 to pipe 17 and thence to the maintaining valve chamber 37 in the valve device 9 and also from pipe 16 to pipe 18 and thence to the equalizing reservoir 10 and equalizing piston chamber 25 in the device 9.

The pressure of fluid thus provided in piston chamber 25 will move piston 24 in a downward direction for thereby actuating the bell crank 29 to open the maintaining valve 36 while allowing the brake pipe discharge valve 31 to remain closed. Upon opening the maintaining valve 36 fluid supplied from the reservoir 2 to the maintaining valve chamber 37 will flow into chamber 26 and thence through pipe 27, the open cut-off valve 14 and out through pipe 78 and the hose coupling 7 to the brake pipe 6 extending through the train whereby said brake pipe and the brake equipments on the several cars of the train will become charged with fluid at the pressure in said reservoir, it being noted that the angle cock 6a at the end of the train opposite that to which the testing device 1 is connected is closed at this time to permit such charging. When the pressure of fluid thus obtained in the brake pipe 6 and in chamber 26 at one side of piston 24 in the valve device 9 becomes substantially equal to that in the equalizing reservoir 10 and in chamber 25 at the opposite side of said piston, spring 39 acting on the maintaining valve 36 will actuate the bell crank 29 and said piston to a position in which the maintaining valve 36 will be closed and the brake pipe discharge valve 31 will also be still closed.

After the brake pipe 6 and brake equipments on the cars of the train have thus become charged to the pressure in the main reservoir 2, the brake inspector will operate the operator's control handle 20 to move the plug valve 19 to its brake application position in which it is shown in Fig. 3 of the drawing. In the brake application position the reservoir 2 will remain connected to the maintaining valve chamber 37, while the equalizing piston chamber 25 and reservoir 10 will be disconnected from reservoir 2 and opened through cavity 22 in the plug valve 19 to the restricted exhaust passage 23 for venting fluid under pressure from said equalizing piston chamber 25 and equalizing reservoir 10. The pressure of fluid in chamber 25 and reservoir 10 will thus be reduced to a degree such as 60 or 55 pounds, assuming that the brake pipe 6 was initially charged to for example 70 pounds, and when the pressure in said chamber and reservoir becomes so reduced the handle 20 will be operated to turn the plug valve 19 to lap position, in which it is shown in Fig. 1 in the drawing, for disconnecting pipe 18 from the atmospheric exhaust passage 23 to thereby terminate the reduction in pressure in chamber 25 and equalizing reservoir 9.

When the pressure of fluid in equalizing piston chamber 25 and equalizing reservoir 10 is reduced as just described to a degree below the pressure of fluid in chamber 26 acting on the opposite side

of piston 24, the latter pressure will actuate said piston in the direction of chamber 25 and thereby operate the bell crank 29 to open the brake pipe discharge valve 31, whereupon fluid under pressure will be vented from the brake pipe 6 past said valve to passage 32 and thence to atmosphere. Fluid will thus be released from the equalizing piston chamber 26 and the brake pipe 6 until the pressure of such fluid becomes reduced to substantially that acting in piston chamber 25 whereupon spring 35 will actuate the bell crank 29 and piston 24 to permit closure of the exhaust valve 31 for thereby limiting the reduction in pressure in brake pipe 6 to substantially the same degree as that acting in chamber 25 and in the equalizing reservoir 10. As well-known when less than a full service reduction in pressure is thus effected in brake pipe 6 in a train the brake controlling valve devices on the cars of the train will operate to apply the brakes to a degree corresponding to such reduction and then move to their lap position in which the brake pipe on the cars is isolated from other parts of the brake equipment on the cars. With the brake pipe on the cars thus isolated the cut-off valve 14 will be closed to disconnect the testing apparatus from the brake pipe and by observation of the pressure gauge 14 for a certain period of time the leakage of fluid under pressure from the brake pipe on the train will be determined.

If the leakage of fluid under pressure from the brake pipe exceeds a certain permissible amount, such as seven pounds per minute, the cut-off valve 14 will be reopened to reconnect the brake pipe 6 to pipe 27 and chamber 26 below the equalizing piston 24. With the operator's valve device 8 still in lap position, as shown in Fig. 1, the pressure of fluid in equalizing piston chamber 25 and in equalizing reservoir 10 is bottled up so that as the pressure in chamber 26 at the opposite side of said piston reduces with brake pipe pressure, due to leakage, the pressure in chamber 25 will actuate said piston to operate the bell-crank 29 to open the maintaining valve 36, whereupon fluid under pressure from the reservoir 2 supplied to pipe 17 will flow to chamber 26 and thence to the brake pipe 6 on the train to build the latter pressure up to that in chamber 25 and equalizing reservoir 10. As the pressure of fluid in the brake pipe 6 is thus increased the piston 24 will be moved in the direction of chamber 25 until the maintaining valve 36 obtains a position for supplying fluid to the brake pipe at a rate just sufficient to maintain the pressure therein against the leakage and equal to the pressure in the equalizing reservoir 10. With the pressure of fluid in the brake pipe thus maintained against leakage the cause of excessive brake pipe leakage will be determined and corrected.

If the brake pipe leakage is within the permissible degree, or after it has been reduced to such a degree, the operator's control device 8 will again be moved to the brake application position (Fig. 3) for effecting a further reduction in pressure in the equalizing reservoir 10 and equalizing piston chamber 25 to a full service degree. The equalizing piston 24 will then respond to effect a corresponding further reduction in pressure in the brake pipe 6 and through subsequent operation of the maintaining valve 36 maintain the brake pipe pressure against leakage at the same degree as acting in the equalizing piston chamber 25 and equalizing reservoir 10. A full service application of the brakes on the train 5 will thus be effected whereupon the inspector will walk

from the brake testing device 1 along the train to the rear end thereof for inspecting the brake equipments on the different cars to determine if they have operated as intended.

- 5 After a full service application of brakes has been effected on the train, and before the inspector leaves the brake testing device 1 to walk back along the train to note if the brake equipments on the car have operated as intended, he will 10 open the cut-off valve 13 of the testing device whereupon fluid under pressure from pipe 27 will flow to pipe 45 and thence into chamber 44 of the fluid pressure wave responsive device 11. When fluid under pressure is thus supplied to 15 chamber 44 it will flow through port 60 in the diaphragm follower boss 58 into chamber 59 and thence around the check valve 61 to chamber 43 and from the latter chamber through port 69 to chamber 46 and charge these three chambers 20 with fluid at the pressure acting in pipe 27 and the brake pipe 6, it being noted that such pressure will be maintained at the same degree as acting in the equalizing piston chamber 25 and equalizing reservoir 10 with the operator's control device 8 in lap position (Fig. 1) due to operation of the maintaining valve 36 as hereinbefore described. With the pressures equal in chambers 44, 43 and 46 of the wave responsive device 11 the bias spring 79 will maintain the diaphragms 30 41 and 42 and associated parts in the position in which they are shown in the drawing and spring 62 will hold the check valve 61 seated closing communication between chamber 43 and passage 48 leading to pipe 49.
- 35 If after inspection the inspector has found that the brake equipments on all cars of the train have operated to apply the brakes as intended, then upon arriving at the end of the train opposite the brake testing device he will momentarily open 40 and then reclose the angle cock 66 at the end of the last car and thereby create a wave of reduction in pressure in the brake pipe 6. This wave of reduction will travel very rapidly throughout the length of the train and become 45 effective in diaphragm chamber 44 of the wave responsive device 11 at the brake testing device 1 and reduce the pressure in said chamber to a degree below that acting in chambers 43 and 46, as a result of which, the higher pressure of 50 fluid in the latter chambers will deflect the diaphragms 41, 42 upward. As the diaphragm 41 is thus deflected upward the follower 53 connected thereto will lift the check valve 61 off of its seat 55 51 to permit fluid under pressure to flow from chambers 44 and 43 to passage 48 and thence to chamber 71 in the fluid motor 12. At the same time fluid under pressure will also flow from chamber 46 through port 69 to chamber 43 and the valve 67 will be opened to accentuate such flow from chamber 46, the fluid thus supplied 60 from chamber 46 to chamber 43 also flowing to chamber 71 in the fluid motor 12. The port 60 through the boss 58 of the follower 52 has such flow capacity with respect to the capacity of port 65 50 and valve 67 for reducing the pressure in chamber 46 that the pressure in the latter chamber will reduce faster than that in chamber 44 so as to destroy the differential in pressures in chambers 44 and 46 whereupon the spring 79 will 70 deflect the diaphragms 41 and 42 back to their normal position to permit closing of valve 61 by spring 62 for terminating supply of fluid under pressure to chamber 71 in the motor 12.

The fluid under pressure supplied, as just described, to chamber 71 in the motor 12 will how-

ever be sufficient to actuate piston 70 against spring 74 to move rod 73 against handle 20 of the operator's valve device 8, which handle is at this time in lap position as shown in Fig. 1, and actuate said handle and the valve 19 from this position to brake pipe charging position in which it is shown in Fig. 2 of the drawing. After the handle 20 is thus moved by fluid motor 12 to its brake pipe charging position the fluid under pressure will be released from chamber 71 in said motor by way of the leakage port 75 to permit spring 74 to actuate piston 70 to retract the rod 73 to its normal position in which it is shown in the drawing.

When the handle 20 and thereby the rotary valve 19 of the operator's control device 8 are thus moved to their brake pipe charging position by operation of motor 12 in response to a wave of reduction effected in the pressure of fluid in the brake pipe by the inspector operating the angle cock 6a at the opposite end of the train, fluid under pressure will be supplied to the brake pipe 6 throughout the train in the same manner as above described for recharging said brake pipe to normal pressure and for in turn operating the brake equipments on the cars throughout the train to their brake release position for effecting a release of the brakes on the cars. After the brakes on the car of the train most remote from the brake testing device 1 have thus released, the inspector will walk from that end of the train back to the brake testing device 1 inspecting all cars to determine if the brake equipment has properly operated to effect a brake release.

After the brake equipments on all cars of the train have been completely tested by operation of the brake testing device 1, as above described, and have been found to operate as intended, the brake testing device at couplings 4 and 7 will be disconnected from the main reservoir 2 and from the train brake pipe 6, respectively, the train now being ready for connection to and movement by a locomotive with the assurance that the brakes will operate as intended.

With the operator's control device 8 in lap position (Fig. 1) after having effected a full service application of the brakes just prior to the inspector walking from the testing device back along the train to the rear end, it will be noted that the maintaining valve 36 will operate during this period to maintain the pressure of fluid in the brake pipe 6 throughout the train against leakage at the same pressure as acting in equalizing reservoir 10. This is very necessary, for otherwise, with permissible leakage of fluid under pressure from the brake pipe the pressure of such fluid, particularly on a long train, would be substantially fully dissipated before the inspector reached the opposite end of the train, so that he would be unable to create a wave of reduction in pressure in the brake pipe for operating the wave responsive device 11 at the testing device by momentarily opening of the angle cock 6a at the rear end of the train.

Summary

It will now be seen that a brake testing device has been provided which requires the service of only one man to check the brake equipment on a whole train and that the one man only has to make one trip from the brake testing device to the opposite end of the train and return to determine if the brake equipment on all cars of the train are operating as intended to cause an ap-

plication of brakes and subsequently a release of such a brake application.

Having now described the invention what I claim as new and desire to secure by Letters 5 Patent, is:

1. A device for testing the air brake equipment on the coupled cars of a train through the medium of the brake pipe extending through the train, comprising in combination, a fluid pressure supply conduit adapted to be connected to a source of fluid under pressure, a brake pipe conduit for connection with said brake pipe at one end of said train, valve means including an operator's control handle movable manually to a first position for operating said valve means to supply fluid under pressure from said supply conduit to said brake pipe conduit, to a second position for releasing fluid under pressure from said brake pipe conduit and to a third position for holding constant reduced pressure of fluid in said brake pipe conduit, a motor piston operable by fluid under pressure to move said handle to its first position, and means subject to pressure of fluid in said brake pipe conduit and an opposing pressure operative in response to a wave of reduction in pressure in said brake pipe conduit relative to said opposing pressure to supply fluid under pressure to said motor for actuating said piston and operative upon substantial equalization of pressure in said brake pipe and said opposing pressure to cut off supply of fluid under pressure to said motor, and means for releasing fluid under pressure from said motor with supply of fluid under pressure thereto cut off.
2. A device for testing the air brake equipment on the coupled cars of a train through the medium of the brake pipe extending through the train, comprising in combination, a fluid pressure supply conduit adapted to be connected to a source of fluid under pressure, a brake pipe conduit for connection with said brake pipe at one end of said train, valve means including an operator's control handle movable manually to a first position for operating said valve means to supply fluid under pressure from said supply conduit to said brake pipe conduit, to a second position for releasing fluid under pressure from said brake pipe conduit and to a third position for holding constant reduced pressure of fluid in said brake pipe conduit, pressure responsive means subject to pressure of fluid in said brake pipe conduit and an opposing pressure operative in response to a reduction in pressure of fluid in said brake pipe conduit relative to said opposing pressure to move said handle to its said first position, and means for rendering said pressure responsive means non-operable in response to a reduction in pressure of fluid in said brake pipe conduit.
3. A device for testing the air brake equipment on the coupled cars of a train through the medium of the brake pipe extending through the train, comprising in combination, a fluid pressure supply conduit adapted to be connected to a source of fluid under pressure, a brake pipe conduit for connection with said brake pipe at one end of said train, valve means including an operator's control handle movable manually to a first position for operating said valve means to supply fluid under pressure from said supply conduit to said brake pipe conduit, to a second position for releasing fluid under pressure from said brake pipe conduit and to a third position for holding constant reduced pressure of fluid in said brake pipe conduit, pressure responsive means

11

subject to pressure of fluid in said brake pipe conduit and a substantially equal opposing pressure and operative upon a reduction in pressure of fluid in said brake pipe conduit relative to said opposing pressure to move said handle to its first position, and means for selectively opening and closing communication between said brake pipe conduit and said valve means and pressure responsive means.

4. A device for testing the air brake equipment on the coupled cars of a train through the medium of the brake pipe extending through the train, comprising in combination, a fluid pressure supply conduit adapted to be connected to a source of fluid under pressure, a brake pipe conduit for connection with said brake pipe at one end of said train, valve means including an operator's control handle movable manually to a first position for operating said valve means to supply fluid under pressure from said supply conduit to said brake pipe conduit, to a second position for releasing fluid under pressure from said brake pipe conduit and to a third position for holding constant reduced pressure of fluid in said brake pipe conduit, a motor operable by fluid under pressure to move said handle to its said first position, and pressure wave responsive means comprising a movable abutment subject to opposing pressures of fluid in said brake pipe conduit and in a chamber and responsive to a wave of reduction in pressure in said brake pipe conduit to open communication from said brake pipe conduit to said motor for supplying fluid under pressure to said motor, and restricting means for equalizing pressure of fluid in said brake pipe conduit and in said chamber.

5. A device for testing the air brake equipment on the coupled cars of a train through the medium of the brake pipe extending through the train, comprising in combination, a fluid pressure supply conduit adapted to be connected to a source of fluid under pressure, a brake pipe conduit for connection with said brake pipe at one end of said train, valve means including an operator's control handle movable manually to a first position for operating said valve means to supply fluid under pressure from said supply conduit to said brake pipe conduit, to a second position for releasing fluid under pressure from said brake pipe conduit and to a third position for holding constant reduced pressure in said brake pipe conduit, a motor operable by fluid under pressure to move said handle to its said first position, and pressure wave responsive means comprising a movable abutment subject to opposing pressure in said brake pipe conduit and in a chamber responsive to a wave of reduction in pressure in said brake pipe conduit to open communication from said chamber to said motor for supplying fluid under pressure from said chamber to said motor, and a restricted communication connecting said brake pipe conduit and chamber for equalizing pressures of fluid therein.

6. A device for testing the air brake equipment on the coupled cars of a train through the medium of the brake pipe extending through the train, comprising in combination, a fluid pressure supply conduit adapted to be connected to a source of fluid under pressure, a brake pipe conduit for connection with said brake pipe at one end of said train, valve means including an operator's control handle movable manually to a first position for operating said valve means to supply fluid under pressure from said supply conduit to said brake pipe conduit, to a second posi-

12

tion for releasing fluid under pressure from said brake pipe conduit and to a third position for holding constant reduced pressure of fluid in said brake pipe conduit, a motor operable by fluid under pressure to move said handle to its said first position and pressure wave responsive means comprising a movable abutment subject to opposing pressures of fluid in said brake pipe conduit and in a chamber and responsive to a wave of reduction in pressure in said brake pipe conduit to open communication from said chamber and brake pipe conduit to said motor for supplying fluid under pressure to actuate said motor, and a restricted communication connecting said brake pipe conduit and chamber for equalizing pressures of fluid therein.

7. A device for selectively opening and closing communication between a source of fluid under pressure and a brake pipe of a train and between said brake pipe and atmosphere for testing the air brakes on the train comprising in combination, a fluid pressure supply conduit adapted to be connected to said source of fluid under pressure, a brake pipe conduit adapted to be connected to said brake pipe, a brake pipe charging and maintaining valve controlling a communication between said supply conduit and said brake pipe conduit, a brake pipe discharge valve controlling a communication between said brake pipe conduit and atmosphere, an equalizing reservoir adapted to be charged with fluid under pressure, an equalizing piston subject opposingly to pressures of fluid in said equalizing reservoir and in said brake pipe conduit, means connecting said charging and discharge valves to said piston, said piston being operative upon a preponderance in pressure of fluid in said reservoir over that in said brake pipe to open said maintaining valve and upon a preponderance in pressure of fluid in said brake pipe conduit over that in said reservoir to open said brake pipe discharge valve and operative upon substantial equalization of said opposing fluid pressures to effect closing of both said maintaining valve and said brake pipe discharge valve, an operator's control device comprising valve means and a handle for moving said valve means to one position for opening said equalizing reservoir to said source of fluid under pressure, to a second position for opening said equalizing reservoir to atmosphere and a third position for bottling up the fluid under pressure in said reservoir, and a manually operative valve for selectively opening and closing the communication through said brake pipe conduit.

8. A device for selectively opening and closing communication between a source of fluid under pressure and a brake pipe of a train and between said brake pipe and atmosphere for testing the air brakes on the train comprising in combination, a fluid pressure supply conduit adapted to be connected to said source of fluid under pressure, a brake pipe conduit adapted to be connected to said brake pipe, a brake pipe charging and maintaining valve controlling a communication between said supply conduit and said brake pipe conduit, a brake pipe discharge valve controlling a communication between said brake pipe conduit and atmosphere, an equalizing reservoir adapted to be charged with fluid under pressure, an equalizing piston subject opposingly to pressures of fluid in said equalizing reservoir and in said brake pipe conduit, means connecting said charging and discharge valves to said piston, said piston being operative upon a preponderance in pressure of fluid in said reservoir over that in said

13

brake pipe to open said maintaining valve and upon a preponderance in pressure of fluid in said brake pipe conduit over that in said reservoir to open said brake pipe discharge valve and operative upon substantial equalization of said opposing fluid pressures to effect closing of both said maintaining valve and said brake pipe discharge valve, an operator's control device comprising valve means and a handle for moving said valve means to one position for opening said equalizing reservoir to said source of fluid under pressure, to a second position for opening said equalizing reservoir to atmosphere and a third position for bottling up the fluid under pressure in said reservoir, actuating means for moving said handle to its said first position, a movable abutment subject to pressure of fluid in said brake pipe and an opposing substantially equal pressure and operative upon a wave of pressure reduction in said brake pipe conduit to effect operation of said actuating means, and manually operable valve means for selectively opening and closing communication between said wave responsive means and through said brake pipe conduit.

9. In train air brake testing apparatus including a source of fluid under pressure, conduit means for conveying fluid under pressure from said source to the brake pipe of the train of coupled cars the brakes of which are to be inspected and tested, a valve in said conduit means having an open position and a closed position, actuating means responsive to a variation in pressure of fluid for shifting said valve from said closed position to said open position, valve means for effecting said variation in pressure in said actuating means and pressure sensitive means subject to pressure of fluid in said brake pipe and an opposing pressure and operative by said opposing pressure upon a wave of pressure reduction in the connection of said conduit means with said brake pipe to effect operation of said valve means

14

5 whereby an attendant at the end of said train remote from said apparatus may initiate a wave of pressure reduction in said brake pipe to effect movement of said valve to said open position for charging said brake pipe with fluid under pressure from said source.

10. In train air brake testing apparatus including a source of fluid under pressure, conduit means for conveying fluid under pressure from 10 said source to the brake pipe of a train of coupled cars the brakes of which are to be inspected and tested, a valve in said conduit, means operable manually for moving said valve to an open position for supplying fluid under pressure from 15 said source to said brake pipe, to a brake application position for releasing fluid under pressure from said brake pipe, and to a lap position for closing communication between the conduit connection with said brake pipe and both said source 20 and atmosphere, power means for shifting said valve to said open position, control means for effecting operation of said power means, and pressure sensitive means subject to pressure of fluid in said brake pipe and an opposing pressure and 25 operative by said opposing pressure upon a wave of pressure reduction in said conduit connection with said brake pipe to effect operation of said control means whereby an attendant at the end of said train remote from said apparatus may 30 initiate a wave of pressure reduction in said brake pipe and effect movement of said valve to said open position for charging said brake pipe with fluid under pressure from said source.
